DESIGN FOR A COMBINED BACKGUARD PANEL AND SUPPORT FOR TIMER, CON- TROLS, AND CONDIMENTS SET FOR STOVES

Ralph E. Kruck, Springfield, Mass., assignor to
Florence Stove Co., Gardner, Mass., a corpora-
tion of Massachusetts

Application March 20, 1939, Serial No. 83,703

Term of patent 3½ years

To all whom it may concern:

Be it known that I, Ralph E. Kruck, a citizen of the United States, residing at Springfield, in the county of Hampden, State of Massachusetts, have invented a new, original, and ornamental Design for a Combined Backguard Panel and Support for Timer, Controls, and Condiment Set for Stoves, of which the following is a specification, reference being had to the accompanying drawing, forming part thereof.

Fig. 1 is a top plan view of a combined backguard panel and support for timer, controls, and

condiment set for stoves showing my new design;

Fig. 2 is a front elevation;

Fig. 3 is an end elevational view thereof looking from the left;

Fig. 4 is an end elevational view thereof looking from the right.

I claim:

The ornamental design for a combined backguard panel and support for timer, controls, and condiment set for stoves, as shown.

RALPH E. KRUCK.
